UNITED STATES PATENT OFFICE.

RUDOLF FROMMER, OF BUDAPEST, AUSTRIA-HUNGARY.

AUTOMATIC FIREARM.

1,169,249.

Specification of Letters Patent. Patented Jan. 25, 1916.

Application filed November 7, 1913. Serial No. 799,650.

To all whom it may concern:

Be it known that I, RUDOLF FROMMER, residing at 158 Soroksári út, Budapest, IX, Austria-Hungary, manager, have invented 5 certain new and useful Improvements in and Relating to Automatic Firearms, of which the following is a specification.

This invention relates to automatic firearms of the kind having sliding barrels and 10 breech blocks of the bolt type in which the breech block is temporarily held in its retracted position by means of a retaining device during the return movement of the barrel to its initial position.

15 The invention has for its object to provide improved arrangements whereby such automatic firearms can be readily converted into hand-loaders. To this end various arrangements have already been proposed 20 according to which the sliding barrel is clamped or otherwise rendered immovable; but it has been found in practice that devices of this kind are open to the disadvantage, among others, that the clamping of the 25 barrel alters the position of the aiming point of the weapon so that a re-adjustment of the sights is necessary when the weapon is converted into a hand loader and vice versa.

My invention obviates this disadvantage 30 by permitting the barrel to retain its normal sliding movement both when the fire-arm is adjusted for hand-loading as well as for automatic loading so that the conditions of operation are the same in both cases

35 and the position of the aiming point remains, therefore, unaltered. This is effected, according to my invention, by so constructing the mechanism that the retaining device above referred to can be rendered in- 40 operative when it is desired to use the weapon as a hand-loader. In that case the breech block after moving backward with the barrel, due to the recoil, is free to return to its original position together with 45 the barrel, the barrel and breech block remaining in engagement with one another both during the backward and forward movement. Consequently the empty cartridge is not ejected, nor is a fresh cartridge

50 automatically introduced into the chamber. In order therefore to fire a second shot, the breech block must be opened by hand, whereupon the empty cartridge is ejected, the reclosing of the breech block introducing 55 a fresh cartridge into the chamber in the usual manner. In other words, when con-

verted into a hand-loader, the action of the weapon at each discharge is similar to that of an ordinary non-automatic firearm, with the exception that, after each discharge, the 60 barrel and breech block move backward under the action of the recoil and immediately return to their original position.

By "automatic fire-arm" I mean a fire-arm in which due to the recoil, *i.e.*, without 65 any action on the part of the operator, the empty cartridge shell is extracted and ejected, a fresh cartridge introduced, the breech block closed and finally the bolt put under tension so that the operator has only 70 to pull the trigger to fire a shot.

By "hand-loader" I mean a fire-arm, in which after each shot the breech-block is moved back by hand to extract and eject the empty cartridge shell, the bolt is put un- 75 der tension and then the breech-block returned to its original position, also by hand, whereby a fresh cartridge is introduced, after which, by pulling the trigger, a shot can be fired, *i.e.*, before each shot the 80 breech-block must be both moved back as also forward again by hand.

The invention is illustrated in the accompanying drawing of which—

Figure 1 is a view in sectional side elevation of the breech portion of an automatic rifle constructed in accordance with my invention, Fig. 2 being a transverse sectional view of a portion of the mechanism shown in Fig. 1.

• In the drawing the sliding barrel of the rifle is indicated at 1 and the breech block at 2. A spring controlled retaining device 3 is provided, adapted to enter a recess 4 in the breech block 2 when the latter is driven 95 backward by the recoil. The breech block 2 is maintained in this position by the catch 3 until the barrel 1 has nearly completed its return movement toward its original position, whereupon a projection 5 engages the 100 catch 3 thereby releasing the breech block 2 and permitting it also to return to its original position as shown in Fig. 1.

The essential feature of my invention consists in providing means for rendering the 105 retaining device 3, or its equivalent, inoperative so as not to prevent the immediate return of the breech block 2 when it is desired to convert the weapon into a hand-loader. In the example shown a small slide 110 6 is provided adapted to have a small transverse movement relative to the casing of the

lock, the extremity 7 of the slide 6 projecting through a slot 8 in the casing and engaging with the recess in the retaining device 3 as clearly shown in Fig. 2.

5 The slide 6 is provided with a flexible tongue 9 having at its free end a knob 11 to which is secured a retaining pin 10.

The casing of the weapon adjacent to the knob 11 is provided with two holes 12 into 10 one or the other of which the retaining pin 10 can enter so that the slide 6 can, by means of the knob 11, be snapped into one or the other of two positions determined by the holes 12.

15 When the slide 6 is in the position shown in Figs. 1 and 2 of the drawings, the pin 10 being in the lower one of the two holes 12, the catch 3 is retained in its lower position out of reach of the breech block 2 so that 20 the latter will move backward and forward together with the sliding barrel 1. Under these conditions the weapon is adjusted for hand-loading and will fire single shots. When, however, the slide 6 is moved upward so as to withdraw the retaining pin 10 from the lower hole 12 and cause it to 25 enter the upper one, the catch 3 will move into the path of the recess 4 so as to retain the breech block 2 in its retracted position

thereby permitting automatic loading to be effected.

My invention is obviously not limited to the precise construction and details above described since any suitable arrangements may be provided for rendering the retaining catch 3 inoperative when it is desired to convert the weapon into a hand-loader, e. g. the catch itself may be arranged to be detachable from the weapon so that its removal will convert the weapon from an automatic to a hand-loading firearm when desired. Improvements in these and other respects may obviously be made without exceeding the scope of my invention.

45 I claim as my invention:

An automatic fire-arm having a sliding barrel, a breech block, a spring actuated catch adapted to retain the said breech block in its retracted position, a projection on the said barrel adapted to disengage the said catch from the said breech block in the foremost position of the said barrel, and means to render the said catch inoperative at will, substantially as and for the purpose set forth.

50 In testimony whereof I affix my signature.

RUDOLF FRÖMMER.
